UNITED STATES PATENT OFFICE.

FREDERIC S. WILLIAMS, OF AMSTERDAM, NEW YORK, ASSIGNOR TO KLAUDER-WELDON DYEING MACHINE COMPANY, OF AMSTERDAM, NEW YORK, A CORPORATION OF NEW YORK.

DYEING-MACHINE.

1,200,677.

Specification of Letters Patent. Patented Oct. 10, 1916.

Application filed February 10, 1915. Serial No. 7,234.

To all whom it may concern:

Be it known that I, FREDERIC S. WILLIAMS, a citizen of the United States, residing at Amsterdam, in the county of 5 Montgomery and State of New York, have invented certain new and useful Improvements in Dyeing-Machines, of which the following is a full, clear, and exact description, such as will enable others skilled in the 10 art to which it appertains to make and use the same.

This invention relates to dyeing machines, washing machines, and the like, and with respect to its more specific features, to machines of the type employing rotatable yarn sticks.

One of the objects of the invention is the provision of a simple and efficient tripping mechanism.

20 Another object of the invention is the provision of a practical tripping mechanism adapted to effectively cause rotation of the yarn sticks as the machine operates to dye materials and which also is of a character 25 to avoid fracture of the machine parts in the event of substantial obstruction to the normal rotation of the yarn sticks.

Other objects will be in part obvious and in part pointed out hereinafter.

30 The invention accordingly consists in the features of construction, combinations of elements and arrangement of parts which will be exemplified in the construction hereinafter set forth, and the scope of the application of which will be indicated in the 35 following claims.

In the accompanying drawings, forming a part of this specification and wherein similar reference characters refer to similar 40 parts throughout the several views, Figure 1 is a perspective view of a portion of a dyeing machine embodying the invention; Fig. 2 represents diagrammatically the relation of the trip and the yarn carrier when 45 the latter first contacts the trip; Fig. 3 is a diagrammatic representation of the parts shown in Fig. 2, when the yarn carrier is obstructed and has been translated further relative to the trip; and Fig. 4 is a diagrammatic representation of the position of 50 the parts as the yarn carrier is translated in a direction reverse to that in normal dyeing.

Referring now more specifically to the 55 drawings, the numeral 1 indicates a casing

adapted to contain dye liquor, and 2 indicates a portion of a reel rotatably mounted so as to dip into the dye liquor. Supported by the reel are the yarn carriers comprising the yarn sticks 3 and 4, arranged in 60 sets on the reel as usual. The outer sticks 3 are preferably square in cross-section and their square ends are received in square sockets, in a rotatable member 6, having arms 7. The members 6 are rotatably 65 mounted on the reel, and are adapted to be rotated in one direction by a trip hereinafter described, reverse rotation of said members being prevented by pawls 8, pivoted on the reel and engaging ratchet 70 teeth 9, on the rotatable members 6. The reel may be rotated by any suitable means, preferably being coupled with a motor so as to be automatically rotated, and thereby translate in a circular path the yarn carried on the sets of sticks, the yarn being thereby carried into and out of the dye liquor as the reel rotates. When the yarn is held in stationary position on the yarn sticks 3 and 4, these sticks in a measure 75 prevent contact of the dye liquor with that portion of the yarn in contact with the stick, resulting in non-uniform dyeing. Hence in this class of dyeing machines it is desirable to move the yarn relative to 80 the sticks so as to equally expose all portions thereof to intimate contact with the dye liquor.

In order to effect this movement of the 85 yarn, a trip 10 is provided, with which trip the arms 7 coöperate, being brought into contact with a projecting portion 11 thereof as they are translated by the reel. The trip 10, in the normal dyeing operation, 90 depends in the translatory path of one or the other of the arms 7, and is designed to offer such resistance to the passage of said arms that the member 6 will be partially rotated by the trip in passing thereby. Should the yarn become entangled in any manner so as to obstruct or prevent 95 rotation of the member 6 by said trip, or should the rotatable member 6 "stick" or be otherwise obstructed or prevented from rotating, there is a tendency to abnormally strain the mechanism, which frequently results in fracture of portions thereof, and especially of the arms 7. The main object of the present invention is to provide a 100 trip mechanism which will offer sufficient 105 110

resistance to the passage of the arms 7 to effect the partial rotation of the members 6, and which is capably of yielding under abnormal strain, so as to avoid the fracture 5 of the mechanism.

In the present embodiment a horizontal rotatable shaft 12, is journaled in a bracket 13, fastened to a suitable part of the frame of the machine. The trip 10 is so connected 10 to the shaft 12 as to rotate said shaft under certain conditions, and preferably this connection involves an eccentric pivoting of the trip relative to the axis of the shaft 12. This eccentric pivoting is accomplished by 15 pivoting the trip at 14, to a bifurcated arm 15 mounted to rotate with the shaft 12, said arm being embodied in a clevis removably fixed to one end of the shaft by a set-screw 16. Also connected to the shaft 12, so as to 20 rotate therewith are abutment faces 17 and 18, transversely disposed relative to said shaft, and respectively on opposite sides of the line joining the pivotal axes of the shaft and the trip, these faces being opposite similar faces 19 and 20 on the trip. It may here 25 be noted that the trip is comprised in an angle lever, the arm 21 of which extends substantially horizontally and serves to gravitatively urge the arm or trip 10 in a direction to cause the abutment face 19 to approach the face 17. The abutment faces 17 and 18 are preferably provided as a part 30 of the clevis or arm 15, with which they may be cast.

35 On the opposite end of the shaft 12 is fastened a lever 22 so as to rotate with the shaft 12, and a weight 23 is carried by the lever 22 and may be positioned at different points thereon in order to vary the effective lever- 40 age. The numeral 24 indicates a stop, preferably a cushioned stop, carried by the bracket 13, and which is so positioned that the lever 22 rests thereon when in its lower position.

45 The drawings show the parts in operative position, and it will be noted that as the reel rotates, the outermost of the arms 7 will successively come into contact with the trip 10. If there is no abnormal obstruction to 50 the rotation of the star-wheel, comprised by the member 6 and the arms 7, in the direction indicated by the arrow *a*, the translatory movement thereof past the trip will result in a partial rotation of the star-wheel 55 and in consequence a partial rotation of the yarn stick carried thereby. Should the rotation of the star-wheel in the direction mentioned be prevented for any reason, the translatory movement of the arm 7 will 60 cause the trip 10 to tend to rotate around its pivotal axis in the clevis 15, but the face 19 being in contact with the stop face 17, such tendency will be transmitted to the shaft 12 and the result will be to cause the weighted 65 lever 22 to rise, and in this wise the trip will

be forced aside by the arm 7 and eventually will escape or wipe past the end of said arm, whereupon it will be restored to its normal operative position, the lever again assuming its lower position against the stop 24. 70 Thus abnormal resistance to the rotation of the star-wheel will cause the forcing aside of the trip 10 under a yielding or gravitational resistance, and there is practically no danger of fracture of any of the parts of 75 the operating mechanism. Also the trip 10 is restored to position in the path of a succeeding star-wheel arm and will effect partial rotation thereof in the usual manner unless the same is obstructed as explained, 80 the effective leverage of the weighted lever being sufficient to cause the partial rotation of the star-wheels, when abnormal resistance to such rotation is not encountered.

It is at times desirable to rotate the reel 85 2 in a reverse direction to that normally employed in dyeing and it will be noticed that though the star-wheels are prevented from reverse rotation by the pawls 8, nevertheless the trip 10 is arranged to freely rotate around its axis in a direction opposite to that above explained, so that said trip offers practically no obstruction to the reverse rotation of the reels. The stop face 18 is designed to coöperate with the face 20 90 to arrest the reverse movement of the trip, so as to prevent the same being turned completely over or into a position in which the arm 21 might operate to hold the trip out of operative position. 100

Thus, by the above described construction are accomplished, among others, the objects hereinbefore referred to.

As many changes could be made in the above construction and many apparently 105 widely different embodiments of this invention could be made without departing from the scope thereof, it is intended that all matter contained in the above description or shown in the accompanying drawings shall 110 be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween.

Having described my invention, what I 115 claim as new and desire to secure by Letters Patent is:

1. In dyeing apparatus or the like, the combination with a stick rotating member, of actuating means therefor comprising a 120 rotatable shaft, means positively preventing rotation of said shaft in one direction and yieldably resisting rotation thereof in the other direction, a tripping dog supported by said shaft, and a connection between 125

said shaft and said dog permitting relative movement of the latter when tending to rotate the former in said one direction and preventing relative movement when tending 5 to rotate said shaft in said other direction.

2. In a dyeing apparatus, or the like, in combination, a translatable yarn carrier comprising a rotatable member, the rotation of which is adapted to effect rotation of 10 the carrier, said member having an arm, a rotatably supported trip adapted to be disposed in the translatory path of said arm, and effect rotation of said member as said member is translated in one direction past 15 said trip, and means permitting said trip to be forced aside by said arm upon abnormal resistance to rotation of said member arm by said trip, comprising a rotary shaft and a lever arm fixed thereto having 20 an adjustably positionable weight adapted to gravitatively resist the forcing aside of said trip.

3. In a dyeing apparatus, or the like, in combination, a translatable yarn carrier 25 comprising a rotatable member, the rotation of which is adapted to effect rotation of the carrier, said member having an arm, a rotatably supported trip adapted to be disposed in the translatory path of said 30 arm, and effect rotation of said member as said member is translated in one direction past said trip, and means permitting said trip to be forced aside by said arm upon abnormal resistance to rotation of said 35 member arm by said trip, comprising a rotatable shaft, an arm rotatable with said shaft and carrying said trip and a weight arm rotatable with said shaft, said shaft having a transverse projection adapted to 40 be contacted by said trip to raise said weight arm.

4. In a dyeing apparatus, or the like, in combination, a translatable yarn carrier comprising a rotatable member, the rotation 45 of which is adapted to effect rotation of the carrier, said member having an arm, a rotatably supported trip adapted to be disposed in the translatory path of said arm, and effect rotation of said member as said 50 member is translated in one direction past said trip, means permitting said trip to be forced aside by said arm upon abnormal resistance to rotation of said member arm by said trip, comprising a rotatable shaft, 55 an arm rotatable with said shaft and carrying said trip and a weight arm rotatable with said shaft, said shaft having a transverse projection adapted to be contacted by said

trip to raise said weight arm, and a stop adapted to determine the low position of 60 said weight arm.

5. In a dyeing apparatus, or the like, in combination, a translatable yarn carrier comprising a rotatable member, the rotation of which is adapted to effect rotation of the 65 carrier, said member having an arm, a rotatably supported trip adapted to be disposed in the translatory path of said arm, and effect rotation of said member as said member is translated in one direction past 70 said trip, means permitting said trip to be forced aside by said arm upon abnormal resistance to rotation of said member arm by said trip, comprising a rotatable shaft and a clevis connected to rotate with said shaft 75 having a plurality of stop faces transversely of said shaft on opposite sides thereof, said trip being rotatably supported by said clevis and having a portion adapted to contact one of said stop faces, and a weight 80 arm rotatable with said trip and having a portion adapted to contact said other stop face.

6. In a dyeing apparatus, or the like, in combination, a bracket, a horizontal shaft 85 rotatably mounted thereon, a weight arm connected to rotate with said shaft, a clevis connected to rotate with said shaft, a trip pivotally connected to said clevis, said clevis having a face adapted to be contacted 90 by said trip to rotate said shaft and raise said weight arm when said trip is rotated in a predetermined direction, and a stop against which said weight arm rests in its lower position. 95

7. In a dyeing apparatus, or the like, in combination, a translatable yarn carrier comprising a rotatable member, the rotation of which is adapted to effect rotation of the carrier, said member having an arm, 100 a pivoted trip adapted to be disposed in the translatory path of said arm, and movable in opposite directions out of said path, and means permitting said trip to be forced aside by said arm upon abnormal resistance 105 to rotation of said member in one direction, comprising a lever arm fixed to said shaft and carrying a weighted member adapted to yieldingly resist said forcing aside of said trip. 110

In testimony whereof I affix my signature, in the presence of two witnesses.

FREDERIC S. WILLIAMS.
